UNITED STATES PATENT OFFICE.

MILO F. WILSON, OF NEW BRIGHTON, PENNSYLVANIA.

ATTACHMENT FOR HORSESHOES.

1,141,596.

Specification of Letters Patent.

Patented June 1, 1915.

Application filed March 13, 1912. Serial No. 683,478.

To all whom it may concern:

Be it known that I, Milo F. Wilson, of New Brighton, in the county of Beaver and State of Pennsylvania, have invented certain new and useful Improvements in Attachments for Horseshoes and the like, of which the following is a specification.

An object of my invention is to provide a new and improved detachable device designed to be applied to horse-shoes and the like to prevent slipping.

In the accompanying drawing, which illustrates applications of my invention, Figure 1 is a bottom plan of a horse-shoe showing my device applied thereto; Fig. 2, a side elevational view representing a portion of a horse's hoof showing the shoe and the anti-slipping attachment applied thereto; Fig. 3, a sectional view taken on line III—III of Fig. 1; Fig. 4, a part sectional view and a part elevational view showing a calk retaining member and a detachable calk in position thereon; and Fig. 5, a view similar to Fig. 4 showing the calk made integral with the attachment and a different form of flange.

Referring to the drawing, 1 designates a horse-shoe provided with a front calk 2 and rear calks 3 of the usual and well known construction.

30 The detachable antislipping device, as illustrated and as preferred, comprises two independent sections, each having a body portion 4 formed at or near the ends thereof with a forward member 5, and a rear member 6, and with an intermediate shoe engaging member 7. Each of the members 5 and 6 are considerably thicker than member 4, thereby providing each member 5 and 6 with a shoe contacting face disposed in a higher horizontal plane than the upper face of the body portion 4, whereby the attachment may be applied to the shoe without interference with the nails by which the shoe is secured to the animal's hoof, and when so applied, the portion 4 is spaced away from the shoe in the manner particularly shown by Fig. 2. Each of the end members 5 and 6 is respectively provided with an upwardly extending inclined flange 8 and 9. The portions 5 and 6 of the form of Fig. 1 are each provided with an opening 10 and 11 designed to receive a removable calk 12. Calks 12 may be threaded as shown by Fig. 4, the threads 13 of which engage threads formed in the respective openings of said members 5 and 6. If desired, however, the calk may be formed

integral with said members 5 and 6 and in the form of Fig. 5 I have shown a calk 12^a formed integral with a member 5^a.

The upwardly extending flanges of the respective members 5 and 6 are designed to engage the inner edge of the shoe, and the said members 5 and 6 are adapted to make contact with the respective front and rear calks of the shoe.

60 Located between said members 5 and 6 and disposed on the opposite edge of the device from the flanges 8 and 9, I provide member 7 with a shoe-engaging flange 14. Instead of forming the flanges of the portions 5, 6 and 7 inclined, said flanges may be straight flanges as 8^a and provided with an inwardly projecting shoulder C designed to engage the upper inner edge of the shoe, this form of flange being shown by Fig. 5.

65 The independent sections constituting the antislipping device may be readily applied to and removed from the shoe. These sections are preferably made of comparatively light spring metal adapted to be sprung into position on the shoe between the front shoe-calk and a rear calk. The dotted lines in Fig. 1 indicate the manner of applying the sections.

70 As will be seen, the members 5 and 6 form end portions of the attachment, while the member 4 acts as a bridge connection therefor. As shown more particularly in Fig. 1, the member 6 has a configuration to substantially fit the heel calk of the horse-shoe, abutting against this calk substantially throughout the width of the shoe, thus causing this calk to not only form a support against endwise movement of the attachment, but in addition, act as a guide in placing the attachment in position and insure that the calks 12 are always located at proper points. While the heel calk acts to prevent movement of the attachment in one direction of its length, the particular shape 75 of the horse-shoe itself serves, in addition to the protection afforded by the front calk of the shoe, to prevent movement in the opposite direction, since such movement would be in a direction to materially increase the tension which is normally placed on the bridge member in use, so that liability of movement of the attachment on the shoe is substantially eliminated.

80 What I claim is:

110 1. An attachment for horse-shoes comprising end portions which carry project-

ing calks with the faces of the portions opposite the calks formed to seat against the exposed face of a horse-shoe, the rear end portion having an end configuration adapted to substantially fit and abut against a heel calk of the horse-shoe substantially throughout the width of the shoe, each end portion having a holding member adapted to engage the shoe and to retain the attachment in position, and a bridge portion connecting the end portions, said bridge portion also having a holding member, said holding members being relatively positioned to require a springing of the front end of the attachment inwardly in applying it to the shoe.

2. An attachment for horse-shoes comprising end portions which carry projecting calks with the faces of the portions opposite the calks formed to seat against the exposed face of a horse-shoe, the rear end portion having an end configuration adapted to substantially fit and abut against a heel calk of the horse-shoe substantially throughout the width of the shoe, each end portion having a holding member adapted to engage the shoe and to retain the attachment in position, and a bridge portion connecting the end portions, said bridge portion also having a holding member, said holding members being relatively positioned to require a springing of the front end of the attachment inwardly in applying it to the shoe, the holding portion of the bridge con-

nexion being adjacent the rear end portion, 35 whereby the springing movement will be substantially restricted to the forward portion of the attachment and permit the rear end portion and heel calk of the shoe to serve as guides in positioning the attachment on the shoe.

3. An attachment for horse-shoes comprising end portions which carry projecting calks with the faces of the portions opposite the calks formed to seat against the exposed 45 face of a horse-shoe, the rear end portion having an end configuration adapted to substantially fit and abut against a heel calk of the horse-shoe substantially throughout the width of the shoe, each end portion having 50 a holding member adapted to engage the shoe and to retain the attachment in position, and a bridge portion connecting the end portions, said bridge portion also having a holding member, said holding members being relatively positioned to require a 55 springing of the front end of the attachment inwardly in applying it to the shoe, said bridging connection extending parallel to and spaced from the face of the shoe, and having a thickness less than the thickness of either end portion.

In testimony whereof I affix my signature in presence of two witnesses.

MILO F. WILSON.
